UNITED STATES PATENT OFFICE.

GEORGE F. RAMM, OF DEL MONTE, CALIFORNIA.

IRONING-BOARD ATTACHMENT.

1,084,482.

Specification of Letters Patent.

Patented Jan. 13, 1914.

Application filed February 7, 1913. Serial No. 746,852.

To all whom it may concern:

Be it known that I, GEORGE F. RAMM, a citizen of the United States, residing at Del Monte, in the county of Monterey and State 5 of California, have invented new and useful Improvements in Ironing-Board Attachments, of which the following is a specification.

The invention relates to ironing boards 10 and has for an object to provide an attachment for securing the covering and padding of an ironing board thereto so as to present a smooth and unwrinkled ironing surface.

The invention embodies, among other features, an attachment whereby the covering and padding will not only be held in position on the board body to provide a smooth ironing surface but which will permit of readily removing the covering or padding 20 when it is desired to repair the same or place a new padding or covering on the board body.

In the further disclosure of the invention reference is to be had to the accompanying 25 drawings, constituting a part of this specification, in which similar characters of reference denote corresponding parts in all the views, and in which:

Figure 1 is a perspective view looking at 30 the under side of the ironing board and showing my attachment applied thereto; Fig. 2 is a transverse sectional view of the ironing board as disclosed in Fig. 1; Fig. 3 is an end view; and Fig. 4 is a vertical longitudinal sectional view showing the handle 35 and securing member as applied to the board body.

Referring more particularly to the views, I disclose an ironing board 10 including a 40 board body 11 of the usual shape provided with a longitudinal groove 12 formed in the edge of the board body and extending around three sides thereof, a padding 13 being adapted to be placed on the board body 45 11, after which a covering 14 is placed over the padding 13 to overlap and cover the edges of the padding as shown. A band 15 is then mounted on the board body to extend around three sides thereof, as shown, and

press the edge of the covering 14 into the 50 groove 12. Bearings 16 are secured to the under side of the board body at the blunt end thereof and mounted to swing on the bearings is a rock shaft 17 having ends 18 bent laterally, with the ends of the band 15 55 secured thereto, a handle 19 being secured to or formed with the rock shaft 17 and adapted to be engaged and held in locked position by a securing member 20 including a hook member 21 for engagement with the free end 60 of the handle and having connection with a rod 22 provided with a hook attached to an eye 23 secured to the under side of the board body 11.

Now when the padding and covering have 65 been placed on the board body in the manner mentioned and the band 15 has been applied to the board body to press the edges of the covering into the groove 12, the handle 19 is swung toward the under side of the board 70 body, thus moving the ends 18 of the rock shaft in the opposite direction to exert a pull on the band and clamp the edges of the covering to the board body and in the groove 12, the handle being secured in retaining position by engaging the hook end of the hook member 21 with the free end of the handle. 75

It will be understood that I do not limit myself to the particular construction disclosed in the drawings and that various 80 changes may be made without departing from the spirit of the invention, the scope of the invention being defined by the appended claim.

Having thus described my invention, I 85 claim:

In an ironing board attachment, the combination with a board body adapted to receive a padding and covering and provided with a groove in the sides thereof, and over 90 which the said covering is adapted to extend, of a band adapted to partially encircle the board body and press the covering into the said groove, a rock shaft journaled on the under side of the board body, with lateral portions of the rock shaft projecting upwardly adjacent the sides of the board body and having the ends of the band secured 95

thereto, a handle carried by the rock shaft and lying beneath the board body, and a securing member mounted to swing on the under side of the board body and adapted for connection with the said handle for holding the same in position to retain the said band in tension.

In testimony whereof I affix my signature in presence of two witnesses.

GEORGE F. RAMM.
